United States Patent

Des. 238,172
Patented Dec. 23, 1975

238,172

WATER PURIFYING AND FILTERING UNIT

George H. Blackstone, 2284 Albion St.,
Toledo, Ohio 43606

Filed Feb. 22, 1974, Ser. No. 444,728

Term of patent 14 years

Int. Cl. D23—01

U.S. Cl. D23—3

Fig. 1

Fig. 2

Fig. 3

FIG. 1 is a front view in elevation of a water purifying and filtering unit showing my new design;

FIG. 2 is a top plan view thereof; and

FIG. 3 is a bottom plan view thereof.

What I claim is:

The ornamental design for a water purifying and filtering unit, substantially as shown.
